United States Patent Office

Des. 226,921
Patented May 15, 1973

226,921

CALCULATOR

George W. Cone, La Jolla, and Donald C. Stephan, San Diego, Calif., assignors to Garrett Comtronics Corporation, San Diego, Calif.

Filed June 5, 1972, Ser. No. 260,060

Term of patent 14 years

Int. Cl. D14—02

U.S. Cl. D26—5 C

FIG. 1 is a front perspective of a calculator showing our new design;

FIG. 2 is a side perspective thereof;

FIG. 3 is a front perspective of a modified form of the calculator shown in FIG. 1, the modification being the addition of a clock thereto; and

FIG. 4 is a side perspective view of FIG. 3.

We claim:

The ornamental design for a calculator, as shown and described.
